6 Claims. (Cl. 124—21)

My invention relates to improvements in marble shooters or guns, and the object of my invention is to make a simple, inexpensive and amusing device which is especially adapted for shooting the toy in playing marbles, so that it will roll along the ground or floor, instead of propelling it through the air. To this end my invention comprises a two piece body portion having a hand grip at its upper rear end, and having its lower end portion formed into a barrel portion, the bottom of the body resting upon the ground, and from which the marble is expelled. My invention is intended to produce a marble shooter of this character in which the body will act as the storage chamber to receive and carry a marble, and with this form of construction, the body, the barrel and the hand grip are arranged so that the lower wall of the body, with the barrel adjacent thereto, can be firmly held upon the ground and easily sighted so that the marble when expelled will roll accurately toward the mark. My invention is further intended to be constructed with a short, or tall body portion so it can be used by the operator in a standing or kneeling position relative to the ground. It is further intended to produce a simple trigger and resilient means for actuating the arm, it acting as a hammer, which will discharge the marble from the barrel with sufficient force to carry it toward the object intended; all of which will be more clearly understood from the description which follows.

Reference is to be had to the accompanying drawings forming a part of this specification, in which similar reference characters indicate corresponding parts in all figures.

FIGURE 1 is a broken side elevation of a pistol type marble shooter embodying my invention;

FIGURE 2 is a front view of the same, taken on line 2—2 of FIG. 1;

FIGURE 3 is a vertical cross sectional view taken on line 3—3 of FIG. 1;

FIGURE 4 is a side view of the shooter shown by FIG. 1;

FIGURE 5 is a top plan view of the hammer arm shown in FIG. 1 and showing the channels for holding the rubber band retaining pin;

FIGURE 6 is an enlarged side view of the rubber band retaining pin;

FIGURE 7 is a fragmentary perspective view of the bolt type clamping means for securing the two free ends of the rubber band shown in FIG. 1;

FIGURE 8 is a side elevational view of the hammer hammer arm release lever;

FIGURE 9 is a top plan view of release lever shown by FIG. 8;

FIGURE 10 is a broken side elevation of modification of the marble shooter embodying a long vertical body portion;

FIGURE 11 is a front view of the marble shooter shown by FIG. 10;

FIGURE 12 is a further modification, a spring being employed in place of the usual rubber band;

FIGURE 13 is a broken side elevation of a pistol type marble shooter embodying a horizontal arranged barrel;

FIGURE 14 is a top plan view of the marble shooter shown by FIG. 13;

FIGURE 15 is a front view of the marble shooter shown by FIGS. 13 and 14;

FIGURE 16 is a broken top plan view of the hollow hammer arm shown by FIG. 13;

2

FIGURE 17 is a side view of the hollow hammer arm as in FIG. 16; and

FIGURE 18 is a side view of the striking pin shown by FIG. 13 where it is assembled within the hollow hammer arm.

In carrying out my invention with the illustrated examples, the device shown by FIGURE 1—9 is provided with a simple box-like main body portion 20 which is adapted to be held vertically, and which is itself equipped with side by side companion sections 21 and 22, having flat bottoms 21' and 22' respectively and as viewed from the front end as in FIG. 2, the right side section 21 being thicker transversely than the left section 22. The section 21 is formed with hollow portions to receive the various working parts, while section 22 acts as a lid or cover. Both sections 21 and 22 provided with concave portions to form the barrel, both sections removably secured together forming the complete barrel 23. The barrel 23 is connected to a vertical tubular magazine by means of a curved tubular section which may be referred to as a chamber, or magazine 26, to carry the marble, or the like, to be shot from the barrel 23. An opening 24 is provided in the side wall of section 22 of sufficient size through which the marble 25 may be inserted and dropped into the magazine 26 and shot from the barrel by the operator. A flexible pin member 27 is arranged in the wall of section 22, and it has a free end extending inwardly and downwardly into the magazine 26 to temporarily retain the marble 25 within the magazine 26; its flexibility permits the marble 25 to pass thereby into the barrel 23 when struck by suitable means.

While the body 20 can be made of any suitable design and material, such as aluminum, steel, plastic or wood, it can be conveniently formed with a hand grip 78 such as a pistol grip and arranged at the top of the body and adjacent the back side and substantially parallel therewith whereby the user can grasp the grip, rest the bottom surface of body 20 upon the ground, and direct the opening of the barrel 23 in the desired direction when he is to use it.

The upper portion of the body section 21 has cut-out portion 28 and has therein a hammer arm 29 secured upon a square portion 30 of a transverse shaft 31 to be rotated thereby when the operator turns the knurled knob 32 arranged outside the body 20 and rigidly secured to the outer end of shaft 31. A rubber band 35 has its free ends 36 secured to the forward lower of body section 21 by means of an angle plate 37 and nut 39 upon threaded bolt 38. The hammer arm 29 is clearly shown by FIGURE 5 with a vertical rubber band passage opening 40, horizontal pin passage 41 shown dotted, and opening 42 to receive stub 43 vertically assembled with pin 44 clearly shown by FIG. 6. The looped portion of the band 35 is positioned over pin 44 and through passage 40 and clamped by nut 39 upon plate 37, the rubber band being stretched as shown by FIG. 1 to draw the hammer arm 29 downwardly when released.

The hammer arm can be retained temporarily in a horizontal position by many ways with a suitable trigger mechanism, and the detail of this connection and of the trigger mechanism without affecting the invention. As shown in FIGURES 1—9, the trigger 45 is pivoted upon pin 46 in the top rear portion of body 20 in the cut-out portion or compartment 47. The trigger is normally held in a forward position by plunger 48 in a horizontal bore 49 by the spring 50 therein. As shown by FIGURES 8 and 9, a link 52 is formed with an off-set rear portion which is pinned to the trigger 45. The link 52 slides horizontally within a groove formed in section 21 between cut-out portion 47 and upper portion of magazine 26. The pointed free end of link 52 projects forwardly and beneath the rear end of hammer arm 29. The sections 21

and 22 are bolted together by suitable means, as well as the two sections of the grip 28 are secured by screw means 55 shown in FIG. 1.

When the shooter shown by FIG. 1 is used it will have a marble in its magazine, the operator will turn the knob 32 clockwise which will elevate the hammer arm to a horizontal position and will be held there by link 52. The operator will sight the device after its placement upon the ground and he will then pull the trigger. The link 52 will allow the hammer arm 29 to drop; it will strike the marble driving it past the flexible pin 27. The hammer arm follows in counter-clockwise direction and expels the marble from the barrel 23 and body 20, as shown dotted in FIG. 4.

In FIGURES 10 through 12 I have shown a slight modification of the trigger mechanism and its connection with the hammer arm, and embodying a body extension so the operator can operate the shooter from a standing position even when the shooter is on the ground; these slight modifications do not affect the principle of the invention. As here shown, the body 20 has a box-like structure 60 extending upwardly from the top rear portion thereof. The pistol grip 78 is arranged here at the top of the box-like structure 60 and on the back side in alignment with bottom of the body 20, so that the user can grasp the grip, rest the body 20 upon the ground, and direct it to the desired point when he is to use it. In FIGURES 10 and 11 the rubber band 35 draws the hammer arm 29 downwardly when the trigger 45 is moved upwardly. A long rod 61 is attached at its upper end with the trigger and at its lower end, inside the box-like structure 60, it is attached to a pin 62 which is secured to a pinion gear 63, the gear mounted upon a pin 64 and in mesh with a rack gear on top of link 65 which is forced outwardly by spring 66 to engage and support the hammer arm 29. When the trigger is pulled, the gear 63 turns in clockwise direction; this moves the rack gear 65 to the left, thereby releasing the hammer arm 29, it being drawn downwardly by rubber band 35, driving any marble in the magazine out the barrel 23 as desired. In FIG. 12, a coil spring 68 replaces the usual rubber band 35. One end 69 of said coil spring 68 is attached to the upper and forward corner of the body 20, while the lower end 70 is attached to a pin inserted in the pivoted end of the hammer arm 29. The operation of the shooter is the same as described with regard to FIGURES 10 and 11. The pinion gear 63 and rack gear 65 however have been eliminated and a shaft 72, pin 73 and slide bar 74 substituted therefor, their operation being obvious from the drawing.

In FIGURES 13 through 18 I have shown a slight modification of the marble projecting mechanisms; however, these modifications do not affect the principle of the invention. The housing 20, grip 78 and rubber band 35 and associated parts are the same as in FIGURE 1. In FIGURES 1 through 12 the magazine 26 and barrel 23 are a continuous curved tubular passageway, the striking arm 29 having its free end traveling from end to end of said passageway. In FIG. 13 the magazine 80 is a short vertical tubular passageway joined by an elbow portion 81 to a short horizontally arranged barrel 82. A marble 25 inserted through opening 24 will drop into the magazine 80, it will roll through elbow portion 81 and against a flexible member 83, extending upwardly and forwardly into the barrel 82. A tubular arm 84 is mounted upon shaft 30, a stepped type hammer pin 85 is assembled within the arm 84 and retained therein by a cap 86 with bore 87 therein; the cap 86 is threaded upon the free end of arm 84. The smaller and lower end 88 of pin 85 normally extends into the elbow portion 81 above and behind the marble 25 in engagement with pin 83. The arm 84 is maintained at substantially 45 degrees with relation to the barrel 82, it being held there by latch member 90 against the tension of rubber band 35. A spring 91 is assembled within the arm 84 behind the pin 85 forcing it

in a downwardly direction, the cap 86 governing the outward travel of the pin 85. The latch member 90 is pivotally mounted upon pin 92, the upper end thereof attached to a coil spring 93, the lower end held in locking engagement with the hollow arm 84 by the coil spring 93. FIGURE 16 shows the rectangular shaped opening 87 in the upper surface of tubular arm 84, the spring being undercut so that the tongue of the latch member 90 will form a tongue and groove fastener with said opening 87. The trigger 45 has a bar-link 96 pivoted therewith and extending forwardly therefrom. A toggle link 97 is pivoted intermediate its ends upon pin 98 located above and to the rear of said latch member 90. The upper end of link 97 is pivotally connected with the outer free end of bar-link 96. When the trigger 45 is drawn backwardly, the bar-link 96 will pull upon the upper end of link 97, the lower end thereof striking the upper end of latch member 90, releasing the tubular arm 84 which is drawn downwardly by rubber band 35. When said arm 84 is moved in counter-clockwise direction by said rubber band 35, the lower free end 88 of pin 85 will strike the marble 25 and travel along with the marble until the arm assumes a vertical position and effecting the marble to leave the barrel 82 under suitable speed and direction. The lower end 99 of the free end portion 88 of pin 85 will strike the bottom of the barrel during the downward and forward travel; however, the spring 91 permits the pin 85 to move upwardly within the arm 84 without any damage thereto. It is clearly seen by FIGURE 17 that the arm 84 is provided with a clamp member 89 with rubber band receiving opening therein. Doubtless other forms of trigger and hammer mechanisms can be used without departing from the invention, and it will be noted that the important thing is to have a two section vertical body with a magazine portion joined with a barrel with horizontal outlet portion, the lower wall of the body adapted to rest upon the ground, and suitable hammer and trigger mechanism combined with rubber band or coil spring structure whereby the single marble in the magazine will be forced out of the barrel in its course straight for the target.

Whereas I have described my invention by reference to a specific form thereof, and a modification, it will be understood that many changes and modifications may be made without departing from the spirit of the invention, a novel, cheap device for shooting the faw in playing marbles.

I claim:

1. A toy marble shooter comprising a vertical body portion, said body portion consisting of two vertical substantially companion body sections joined together, said body portion having a flat bottom horizontally arranged and adapted to rest upon the ground when in use, said body portion embodying a vertical magazine chamber and a tubular barrel joined together, an opening in the side wall of one of said vertical body sections for permitting insertion of a marble into the magazine chamber, a resilient pin member secured to the rear wall of one of said body sections and with its free end extending inwardly and downwardly into said vertical magazine chamber for retaining a marble temporarily in said magazine chamber, a transversely arranged shaft located in the upper forward portion of said body portion, a vertically swingable hammer-arm pivotally mounted on said shaft, said hammer-arm having a rear free end which swings downwardly and forwardly in a counter-clockwise direction to expel the marble from the said tubular barrel, a hand grip extending from the upper rear end portion of said body portion, trigger mechanism arranged in the upper rear end portion of said body portion for controlling the hammer-arm pivotally mounted at the forward end of said body portion, a finger of said trigger mechanism extending downwardly between said hand grip and said body portion, and a rubber band secured to the inner forward lower portion of said body portion and to the rear free

end portion of said hammer-arm for urging said hammer-arm in said counterclockwise direction.

2. A toy marble shooter comprising a vertical body portion, said body portion consisting solely of two vertical substantially companion body sections joined together by suitable means, said body portion having a flat bottom horizontally arranged and adapted to rest upon the ground when in use, said body portion embodying a vertical magazine chamber therein and a tubular barrel joined together, an opening in the vertical side wall of one of said vertical body sections for permitting insertion of a marble into said magazine chamber, a resilient member secured to the rear inner wall of said body portion with its free end extending inwardly and downwardly into said vertical magazine chamber for retaining a marble temporarily in said magazine chamber, a shaft mounted transversely in horizontally aligned bores in both of said body sections and adjacent the upper forward end portion of said body portion, a vertically swingable hammer-arm pivotally mounted upon said shaft, said hammer-arm having a rear free end which swings downwardly and forwardly in a counter-clockwise direction to expel the marble from the said tubular barrel, a hand grip extending rearwardly and downwardly from the upper rear portion of said body portion, trigger mechanism arranged in the upper end portion of said body portion and said hand grip for controlling the hammer-arm mounted on said transverse arranged shaft, said shaft having means mounted upon one end thereof for rotating said hammer-arm to move it into an upper horizontal position and into a position for engagement with said trigger mechanism, a finger of said trigger mechanism extending downwardly between said hand grip and said body portion, and a rubber band secured to the inner forward and lower portion of said body portion and also to the rear free end portion of said hammer-arm for urging said hammer-arm in said counterclockwise direction.

3. The toy marble shooter according to claim 2 wherein said hammer-arm embodies an opening therein through which said rubber band extends and also embodies a removable pin to assemble the rubber band with said hammer-arm.

4. A toy marble shooter of the kind described comprising a vertical body portion adapted for location in vertical position, and a hand grip extending rearwardly and downwardly from the upper rear end portion of said body portion, said body portion consisting of two vertical substantially companion body sections joined together by suitable means, said body portion having a flat bottom horizontally arranged and adapted to rest upon the ground when in use, one of said body sections being thicker transversely than the other, said body portion embodying an inner vertical magazine chamber and a tubular barrel joined together, an opening in the side wall of one of said vertical body sections for permitting insertion of a marble into the said magazine chamber, a transversely arranged shaft located in the upper forward portion of said body portion, a vertically swingable hammer-arm pivotally mounted upon said shaft, said hammer-arm having a rear free end which swings downwardly and forwardly in a counterclockwise direction to expel the marble from the said tubular barrel, a trigger mechanism for controlling said hammer-arm, a rubber band rigidly secured at one end thereof to said body and its opposite end assembled to said hammer-arm at the rear free end thereof whereby said rubber band is under tension when in a restricted horizontal position under the control of said trigger mech-

anism, a striking pin, said hammer-arm being tubular with said striking pin resiliently held in the lower end thereof.

5. A marble shooter of the kind described comprising a vertical body portion composed of a pair of companion vertical body sections, a hand grip extending rearwardly and downwardly from the upper rear end portion of said body portion, a vertical tubular marble magazine chamber within said body portion, a horizontal tubular marble barrel arranged in the bottom portion of said body portion, a curved tubular passageway joining said magazine with said barrel, a vertically swingable hammer-arm pivotally mounted with a shaft arranged transversely in the forward portion of said body portion, said hammer-arm having a rear free end which is able to swing downwardly and forwardly in a counterclockwise direction to expel the marble from the said tubular barrel, a transversely disposed solid cylindrical shaft, trigger mechanism adjacent to the hand grip for controlling the action of said hammer-arm, said trigger mechanism embodying a tubular shaft mounted upon said solid shaft, said tubular shaft having a pair of pins extending outwardly therefrom, a trigger forming a part of said trigger mechanism, one pin extending outwardly and horizontally and connected by means of a rod with said trigger, a link horizontally and slidably movable beneath the free end of the said hammer-arm whereby said hammer-arm is held under tension and control, the other pin extending downwardly through said link.

6. A device for shooting the taw in playing marbles, having a body portion composed of a pair of vertical body companion sections secured together, one of said body sections being thicker than the other, a hand grip integrally secured with the top rear portions of said body sections, a marble magazine arranged within said body with its upper end extending vertically upwardly, said magazine having resilient means attached to its rear wall and extending forwardly and downwardly therein, said resilient means to retain temporarily a taw to be projected, a barrel within the lower part of said body with its rear end joined with said magazine and having its opposite end portion extending horizontally and forwardly, a transversely arranged shaft located in and extending between said body sections at the upper forward portion thereof, a vertically swingable hammer-arm mounted upon said shaft, the rear end of said hammer-arm swingable through said magazine and said barrel, a spring having one end thereof attached to said hammer-arm adjacent its rear end, the opposite end of said spring attached to the body section of greater thickness, said spring adapted to be stressed and deformed while said hammer-arm is in a raised horizontal position for striking a taw when released, means connected with said transversely arranged shaft for rotating said hammer-arm to move it into an upper horizontal position, and trigger means located in said body portion and said grip to release said hammer-arm and the stressed spring when said hammer-arm is in its horizontal position.
